UNITED STATES PATENT OFFICE.

GEORGE JACOBS, OF DETROIT, MICHIGAN.

GARAGE.

Application filed April 24, 1924. Serial No. 708,632.

This invention relates to garages for the storage of motor vehicles, and its object is to build a structure of this character in sections with an elevator for each section and means to move the elevators up or down to positions in alignment with superimposed bays or chambers in which the vehicles may be stored and from which they may be taken by the elevator.

10 This invention consists, in combination with a vertical framework consisting of superimposed bays of sufficient length, width and height to receive motor vehicles, of an elevator and mechanism to move it up and down to position it opposite any one of the bays, a platform mounted in each bay and supports therefor to permit the platform and its load to be moved from the bay into the elevator and back into the bay, means on the elevator to lift a motor vehicle and hold it suspended and to lower it onto a platform which has been moved out of a bay into the elevator, and mechanism mounted on the elevator for moving the platforms into and out of the bays.

15 It further consists of the details of construction illustrated in the accompanying drawings and particularly pointed out in the claims.

20 In the drawings, Fig. 1 is an elevation of the framework of this improved garage, two sections of bays and the elevators therefor being shown. Fig. 2 is a plan of two opposite bays and an elevator between them.

25 Fig. 3 is a longitudinal vertical section of the elevator. Fig. 4 is an end elevation thereof. Fig. 5 is a side elevation thereof. Fig. 6 is a detail of the locking mechanism. Fig. 7 is a detail of the supporting means for the vehicle.

Similar reference characters refer to like parts throughout the several views.

Suggestions have been made that down town parking garages be built with two vertical sections of any desired length comprising superimposed bays and an elevator adjustably supported by a traveling crane which is adapted to move back and forth the length of the garage and thus position the elevator in front of any one of the bays. I prefer to construct my garage of sections of considerable height and to provide an elevator between each two spaced sections of bays so that there will be an elevator for each of a limited number of vehicle bays. I thus avoid the delays which result at the

opening and close of the business day from too many vehicles for one elevator.

In Figs. 1 and 2 I have conventionally shown a framework comprising the outside I-beam posts 1 connected by horizontal channels 2 and 3 and horizontal I-beams 4. Pairs of inner posts 5, preferably of I-beam sections, extend upwardly between adjacent girders 4. Hoisting devices are mounted centrally of the space between the inner posts 5 and are shown conventionally to consist of a motor 6, a worm 7 on its armature shaft, and a longitudinal shaft 8 mounted in any desired manner in the framework and carrying the hoisting drums 9 and the worm wheel 10 meshing with the worm 7. Cables 11 on the drums extend down to the carriage or elevator.

The vehicles to be stored are placed on movable platforms of which there is one for each bay. The platforms are shown to consist of two horizontal plates or beams 13 connected at their ends by cross bars 14. A sheet metal floor 15 may be attached to the lower sides of the I-beams 4, if desired. Stub shafts 16 extend from the cross bars 14 and receive the wheels 17 which run on the lower flanges of the I-beams 4 so that the platform may extend across the space between the four posts 5. As indicated in Fig. 1, the I-beams 4 are replaced by channel beams 3 at the transverse end wall 19.

The carriage or elevator may be of any desired type of construction. It preferably comprises a roof plate 21 attached to side channel bars 22 between which are the cross bars 23. Outside of the channel bars 22 are the upright angle bars 24 which are connected by the end plates 25. I also prefer to connect the angle bars 24 by the longitudinal bars 26. A guide bar 27 is attached to each end plate 25 and is slidable in the vertical guide channels 28 which extend between the I-beams 4.

100 Mounted on the roof plate 21 of the elevator is an electric motor 30 of the reversible type whose armature shaft 31 carries a pinion 32 which meshes with the gear 34 on the longitudinal shaft 35. On both ends of this shaft are sprocket wheels 36 which carry a chain 37 that also passes around the sprocket wheels 38 on the pins 39. Each chain carries two pins 40 and 41 which are adapted to enter the notches 42 in the control levers 43. See Fig. 4. The lower run of each chain may be guided by the plate 45

at the lower edge of the adjacent end plate 25 and by the channel 46 just above it.

If the motor is energized to turn clockwise in Fig. 4, the left runs of the two chains come down and the pins 40 thereon enter the notches 42 in the levers 43 on the platform of the bays on the left side and push down these levers against the pressure of the springs 47. Continued movement of these 10 chains will pull the platform to the right into the carriage, the plates 13 passing below the lower edges of the end plates 25 of the elevator. If the motor is now reversed the platform will be pushed back into the bay, 15 either loaded or empty. Pins 48 prevent the levers 43 from rising too far.

The means for loading and unloading the elevator are operated by a reversible motor 50, also mounted on the roof plate of the 20 elevator. A pinion 51 on its armature shaft meshes with a gear 52 on one end of a double screw 53. The central bearing 54 of this screw is secured to the roof plate 21 and the screw is both right and left handed so that 25 the nuts 55 thereon will move together inwardly or outwardly as the screw is turned.

The nuts 55 are attached to the cross bars 56 which are supported by the rollers 57 running on the lower flanges of the channels 30 22. Upright bars 58 in pairs (Fig. 3) extend down from each of these cross bars adjacent these rollers and the links 59 are pivoted to the lower ends of these bars 58. Cross shafts 60 and 61 connect the links 59 35 of each pair of bars 58 and a roller 62 may be mounted on each shaft. An inclined bar 64 extends from the pivot 65 of each corner bar 24 to a pin 66 slidable in the slot 67 in each bar 58 and a link 68 connects the shaft 40 60 to the pin 69 on the bar 64.

When the bars 58 are moved outward by the screw 53, the pin 66 is slid upward, carrying with it the link 70 which connects to a pin 71 on the link 59 and this 45 swings up the link 59 until it is parallel with the bars 24. When the elevator has been lowered down over an automobile standing on a platform or on the ground floor, and the screw 33 is turned to pull the nuts 55 toward each other, then the shafts 60 are forced in under the automobile wheels 74, as indicated in Fig. 7, raising the wheels until 50 they rest on the rollers 62. The vehicle may now be carried to any desired point, the outer shaft 61 being prevented from swinging down by the links 70. As each of these 55 supporting devices can be made operative to support a wheel within a range of about twelve inches, the same elevator can be employed to take care of all but the shortest and the longest automobiles.

Another suspension mechanism is shown in Fig. 5. The links 68 and 70 of Fig. 3 are omitted but a supporting link 76 extends 60 down from the pin 77 on the bar 58 and has

a slot 78 to receive the pin 71. This link 76 prevents the link 58 from swinging down to below horizontal position. The heavy spring 79 will swing the link 58' up to vertical position when there is no load on the shafts 60 70 and 61. The bars 58 are again kept vertical by the bars 64 and 68.

I prefer to lock the elevator in proper position before loading or unloading. A simple lock consists of holes 80 in the guide 75 channels 28 and holes 81 in the guides 27 on the end plates 25. Two longitudinally movable bars 83 and 84 extend to the vertical shaft 85 mounted at a convenient position and connect to an operating lever 86 by 80 means of links 87. This lever may be mounted on the shaft 85 which may be mounted on a small controlling platform 89 where the operator may stand adjacent to his operating device 90 for the motors. 85

The lengths of the sections will preferably vary with the lengths of the vehicles to be stored as garages of the type described will be erected where ground is of great value. The widths and heights of the bays need not be over seven feet to accommodate the usual 90 passenger vehicles, but the lengths may vary from fourteen to twenty feet. As the sections can be of any desired height, this garage may be attached to apartment houses 95 and office buildings or be erected independently thereof. A building sixty feet wide, one hundred twenty feet long and one hundred feet high would have three drive ways, twenty-one elevators and storage space for 100 nearly six hundred automobiles of average wheel base. The hoods of the vehicles would be under the operators' platforms of the elevators. Each stored vehicle would be accessible only from an elevator and could be removed from the garage only through the use of the elevators. As no space is 105 wasted, more vehicles can be stored in a garage of this character than in any other hitherto suggested wherein each vehicle is 110 accessible at all times.

The details of construction and the proportions of the parts may be changed by those skilled in the art without departing 115 from the spirit of my invention as set forth in the following claims.

I claim:—

1. In a building, a series of superimposed 120 storage bays and horizontally movable platforms therein, an elevator, means to raise and lower the elevator to position it opposite any desired bay, means on the elevator to engage and carry a load, and means on the elevator to move the platforms out of the bays under the load and then back into the bays. 125

2. In a building, a series of superimposed storage bays embodying a horizontal track at each end of each bay, a platform for each bay and rollers at the ends thereof adapted 130

- to travel on said tracks, an elevator, means to raise and lower the elevator to position it opposite any desired bay, means on the elevator to engage and carry a load, and 5 means on the elevator to move the platforms out of the bays under the load and then back into the bays.
3. In a building, a series of superimposed storage bays and horizontally movable platforms therein, an elevator, means to raise and lower the elevator to position it opposite any desired bay, means on the elevator to support a load, means to lock the elevator opposite any desired bay, and means on the 10 elevator to move the platforms out of the bays under the loads and then back into the bays.
4. In a building, a series of superimposed storage bays and horizontally movable platforms therein, an elevator, guiding means therefor, means to raise and lower the elevator to position it opposite any desired bay, means to lock the elevator opposite any desired bay comprising means on the elevator 15 to engage in recesses in the guiding means, means on the elevator to support a load, and means on the elevator to move the platforms out of the bays and under the loads and back into the bays.
- 20 5. In a building, a series of superimposed storage bays and platforms therein, an elevator, means to raise and lower the elevator to position it opposite any desired bay, a pair of load receivers carried by the elevator, and means to move said load receivers toward each other under a load, said platforms being movable out of the bays underneath the load and said load receivers being separable to deposit the load on the platforms.
- 25 6. In a building, a series of superimposed storage bays and platforms therein, an elevator, means to raise and lower the elevator to position it opposite any desired bay, load supporting means on the elevator, and means 30 to move a platform from its bay to position beneath the load comprising a chain at each end of the elevator, a notched lever on each end of the platform, a pin on each chain to engage in the notch of the adjacent lever, and means to actuate the chain to move the 35 platform in either direction.
7. In a building, a series of superimposed storage bays and platforms therein, an elevator, means to raise and lower the elevator to position it opposite any desired bay, load supporting means on the elevator, a notched lever at each end of the platform, a driving sprocket wheel and two guiding wheels at each end of the elevator, a chain passing around said wheels at each end of the elevator and having its run between two of the wheels substantially horizontal, a pin on each chain adapted to engage in the notch of an adjacent lever and to move the lever and platform horizontally into and out of the 40 bay, and means to actuate said driving sprocket wheel.
8. In a building, a series of superimposed storage bays and platforms therein horizontally movable into and out of the bays, an elevator, means to raise and lower the elevator to position it opposite any desired bay, a reversible shaft rotatable mounted at the top of the elevator and having right and left threads, nuts on said threaded portions 45 of the shaft, cross bars attached to said nuts and pairs of vertical bars extending down from each of said cross bars, means to keep the bars vertical, a transverse shaft connecting the lower ends of each pair of vertical bars, a pair of links connected to each transverse shaft, a second shaft carried by each pair of links, means to support the links in horizontal position to receive a load on said shafts, and means to swing the links to vertical position when the nuts are at the outer ends of the threaded portions on which they are mounted.

GEORGE JACOBS.
